THREAD-CONTROLLING MECHANISM FOR
SEWING MACHINES

Edward B. Allen and Maurice D. Knox, Newtown, Conn., assignors to The Singer Manufacturing Company, Elizabeth, N. J., a corporation of New Jersey

Original application May 4, 1932, Serial No. 609,083. Divided and this application August 8, 1933, Serial No. 684,142

2 Claims. (Cl. 112—247)

This invention relates to sewing machines, more particularly of the buttonhole sewing type disclosed in our copending application Serial No. 609,083, filed May 4, 1932, of which this application is a division.

The invention has for an object to provide a sewing machine of this type with means for preventing the stealing of needle-thread from the supply by the usual check-spring when the tension device is opened at the end of a sewing operation, whereby the initial stitches of the next sewing operation may be properly formed and set. With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

In the accompanying drawings, Fig. 1 is a side elevation of a buttonhole sewing machine embodying the invention. Fig. 2 is a rear end elevation of the machine. Fig. 3 is a front end elevation of the machine. Fig. 4 is a view showing the action of the check-spring blocking mechanism associated with the tension release mechanism. Fig. 5 is a top plan view of the upper work-clamp-foot, and Fig. 6 is a top plan view of the tension device and check-spring blocking means.

The machine chosen for the purposes of the present disclosure has a frame including the bed 1, from which rises the hollow standard 2 of the gooseneck 3 terminating in the head 4. Journaled in the gooseneck 3 is the main-shaft 5 having at its front end the take-up operating crank 6 and the needle-bar reciprocating crank 7 which is connected by the link 8 to the needle-bar 9 carrying the needle 9' and journaled in the usual needle-bar gate 10 which is fulcrumed at 11 to perform vibrating movements. The take-up crank 6 actuates the usual bell-crank take-up lever 12, Fig. 3, which is anchored by the link 13 to the head 4.

The work-clamp is of usual construction and comprises the upper rectangularly apertured clamp-foot 14 carried by the clamp-lever 15 fulcrumed at 16 on the longitudinal slide frame 17 mounted in the cross-slide frame 18; the frames 17 and 18 being actuated through the usual connections with the feed-wheel 19 to shift the work-clamp for the proper placing of the stitches to form the button hole.

The stop-motion device is preferably constructed substantially in accordance with the disclosure of the Allen and Myers Patent No. 1,878,091; dated September 20, 1932. It comprises the usual tilting stop-motion lever 20 fulcrumed at 21 and carrying the upwardly spring-pressed stop-plunger 22 which cooperates with the stop-cam 23 connected to the main-shaft 5. When the machine is running, the stop-motion lever 20 is tilted about its fulcrum 21 to carry the upper end of the plunger 22, Fig. 1, to the right and out of range of the stop-cam 23. When the stop-motion lever 20 is released to stop the machine, it returns to its vertical position, Fig. 1, and carries the spring-pressed stop-plunger 22 into the path of the stop-cam 23 which first depresses the plunger 22 and finally permits the plunger to rise into a stop notch 23' in the cam and stop the machine at a predetermined point with the needle 9' out of the work and the take-up 12 at its highest point.

The stop plunger 22 carries the usual laterally extending block 24 which engages under the spring-pressed plunger 25 in the arm 26 of the usual stop-motion-controlled rock-shaft 27 and gives such rock-shaft an impulse as the plunger 22 rises to final stopping position in the notched stop-cam 23. This impulse given to the rock-shaft 27 is utilized for various purposes in a machine of the present type, notably for releasing the tension device 28, as will be hereinafter described.

The needle 9' cooperates with the rotary hook mechanism 29 to form stitches, as disclosed in our said copending application.

The needle-thread *t* runs from the supply through the top tension-device 30, thence around the thread-guide 31 and through the side tension-device 28; thence past the guide 32 and through the check-spring 33 and under the guide 34 to the take-up 12 and down to the needle 9'.

At the end of a sewing operation the upper tension-device 30 is opened by the wedge-bar 35, Fig. 1, connected to the lever 36 which is connected by a link 37 to the tilting stop-motion lever 20. The side tension 28 is opened by the wedge-ended curved arm 38 carried by the rock-shaft 39 journaled in the head 4 and having fixed to it a rearwardly extending arm 40 carrying a ball 40' engaging the forked end 41' of an arm 41 fixed to the stop-motion controlled rock-shaft 27, Fig. 3. The side tension 28 applies a uniform tension to the needle-thread at all times when the machine is sewing. The check-spring 33 performs its usual function of taking up the slack 110

thread between the eye of the descending needle 9' and the work. The upper tension-device 30 is automatically controlled to apply various additional amounts of tension to the needle-thread 5 to meet the requirements of sewing the first side, the return side and the barring stitches at the ends of the buttonhole. The mechanism for operating the upper tension-device during the sewing will not be described herein as it forms no 10 part of the present invention.

At the end of a sewing operation the needle-thread *t* is cut and nipped by the usual needle-thread cutter and nipper 42, Figs. 4 and 5, carried by the clamp-foot 14 and actuated by the spring-retracted rod 43 which is released by the upward movement of the arm 44 when the operator pulls down on the lever 45 to open the work-clamp. This mechanism is constructed substantially in accordance with the disclosure of the clamp-opening and needle-thread-cutter-tripping mechanism in the Allen application Serial No. 551,114; filed July 16, 1931.

The present machine is designed more particularly to sew a pyramid purl stitch which is 25 accomplished by the cooperation of an upper eye-pointed zigzag or laterally vibrating needle with an under thread-mass or bobbin associated with a loop-taker which seizes thread-loops from the needle below the work and expands such loops 30 for passage about the under thread-mass or bobbin. The needle-thread take-up is required not only to draw up the needle-thread loops after they have been interlocked with the bobbin-thread, but also to draw such loops entirely 35 through the work, pulling loops of bobbin-thread through to the upper side of the work, so that in the finished seam the needle-thread will lie in substantially a straight center line between the rows of zigzag needle-punctures, while loops of 40 bobbin-thread emerge from the needle-punctures at the upper side of the work and embrace the straight needle-thread. In the formation of such a pyramid-purl seam along the sides of a buttonhole, about twenty-thousandths of an inch of 45 needle-thread is used per stitch while about three-sixteenths of an inch of bobbin-thread must be supplied from the bobbin and pulled upwardly through the work by the take-up in drawing up the needle-thread loop. The tension 50 on the bobbin-thread must necessarily be light while the tension on the needle-thread must be very strong.

It will be evident that when the machine is 55 sewing, every time the take-up moves to its highest point the strain on the needle-thread over-

comes the weak tension of the check-spring and pulls it over to the strained position shown in full lines in Fig. 4. At the end of a sewing operation the tension-devices are automatically opened and the check-spring has a tendency to recover its initial or dotted line position, Fig. 4, and steal needle-thread through the open tension-devices. If this action were permitted to occur at the end of a sewing operation with the needle-thread end held in the nipper in the clamp-foot, the machine would have to make several stitches in the next buttonhole producing cycle to use up the slack needle-thread stolen from the supply by the check-spring. During the sewing of these several stitches the bobbin-thread loops would not be properly pulled to the upper side of the work and defective stitching would result. To overcome this difficulty there has been secured to the tension-opening arm 38 a check-spring blocking arm 46 having a V-throat 47, Fig. 6, in its free end adapted to hold the check-spring in its fully strained position, Fig. 4, to prevent such spring from recovering, when the tension-devices are opened and stealing thread from the supply.

Having thus set forth the nature of the invention, what we claim herein is:—

1. In a sewing machine, in combination, stitch-forming mechanism including a reciprocating needle, a loop-taker, a take-up, a tension-device, a check-spring, a needle-thread cutter and nipper, a stop-motion device for the stitch-forming mechanism arranged to stop the latter with the take-up at the end of its stitch-setting action and the check-spring under the strain of the needle-thread, means for opening the tension-device, and means for holding the check-spring in its strained position while the tension-device is open.

2. In a buttonhole sewing machine, in combination, a reciprocating needle, a loop-taker, a work-clamp, a stop-motion device, a take-up, a tension-device, a check-spring associated with said tension-device, tension-release mechanism connected to be operated by said stop-motion device, a needle-thread cutter and nipper on said work-clamp, and means connected with said tension-release mechanism for blocking the recovery motion of the check-spring to prevent the check-spring from stealing thread from the supply through the released tension-device.

EDWARD B. ALLEN.
MAURICE D. KNOX.
